UNITED STATES PATENT OFFICE.

JOHN E. LITTLE, OF PRINCETON, INDIANA.

GATE.

SPECIFICATION forming part of Letters Patent No. 350,374, dated October 5, 1886.

Application filed June 21, 1886. Serial No. 205,812. (No model.)

To all whom it may concern:

Be it known that I, JOHN E. LITTLE, a citizen of the United States, residing at Princeton, in the county of Gibson and State of Indiana, 5 have invented certain new and useful Improvements in Gates, of which the following is a specification, reference being had therein to the accompanying drawings.

This invention relates to certain improvements in gates, doors, and the like, being specially designed for farm-gates, barn-doors, and other similar hinged devices, which are liable to sag toward the unsupported end; and it has for its objects, primarily, to prevent such 15 sagging and the pulling of the supporting-post forward, and to compensate for the sagging when such has taken place, either in new or old gates or doors, and also to provide for elevating the unsupported end of the gate to 20 clear snow-drifts or provide a passage underneath the same for small stock, as more fully hereinafter specified. These objects I attain by the means illustrated in the accompanying drawings, in which—

25 Figure 1 represents an elevation of my improved gate, showing the same in a normal position, and Fig. 2 a similar view, showing the gate in an elevated position.

The letters A and B indicate the fence-posts, 30 which are driven in the ground or supported in any other convenient manner. The post B is provided with pintles C in proper positions to receive the hinge-sections of the gate, as more fully hereinafter explained.

35 The letter A' indicates the gate, which is composed of a series of parallel bars, a, connected by vertical bars b b' b'.

The letter c indicates the upper hinge-section of the gate, which is looped around the 40 upper pintle so as to permit the gate to swing freely, the said section being bolted to the corner of the gate, as shown.

The letter D indicates an oblique beam ex-

tending through loops d, arranged at the lower and upper ends of the vertical bars b' b', respectively. The upper end of the beam D is provided with a series of oblique notches, d', which are adapted to engage, singly, the lower portion of the upper loop d, so as to hold the gate either in a normal position, as shown in Fig. 1, or in an adjusted elevated position, as shown in Fig. 2 of the drawings. The lower end of the oblique beam has secured to it the lower hinge-section, which is looped around the lower pintle so as to permit the said beam to swing thereon and allow the gate to be conveniently opened or closed. The free end of the gate is provided with a bolt, e, which engages a catch, g, on the post A, to lock the gate when closed. It will be seen that as thus constructed the gate can be elevated at the end liable to sag, so as to keep it true at all times, and also that it may be raised, when desired, at the free end, for any purpose that may be required.

I am aware that gates have heretofore been constructed having pivoted bars, which are notched, and devices for engaging the same, so as to hold the gate in an adjusted elevated position, and such I do not claim, broadly.

Having thus described my invention, what I claim, and desire to secure by Letters Patent, is—

The combination, with the post B and the pintles C, of the oblique beam extending through the loops d, and having a series of oblique notches adapted to engage the upper loop, the gate and beam being provided with hinge-sections looped around the pintles, respectively, substantially as specified.

In testimony whereof I affix my signature in presence of two witnesses.

JOHN E. LITTLE.
